UNITED STATES PATENT OFFICE

ROBERT T. COTTAM, OF HIGH POINT, NORTH CAROLINA, ASSIGNOR OF ONE-HALF TO JOSEPH D. COX, OF HIGH POINT, NORTH CAROLINA

DESIGN FOR A TRICYCLE OR THE LIKE

Application filed October 20, 1930. Serial No. 37,316. Term of patent 7 years.

To all whom it may concern:

Be it known that I, ROBERT T. COTTAM, a citizen of the United States, residing at High Point, in the county of Guilford and State of North Carolina, have invented a new, original, and ornamental Design for a Tricycle or the like, of which the following is a specification, reference being had to the accompanying drawings, forming part thereof.

cycle embodying my new design and showing the front and parts of the side and top thereof.

Figure 2 is a perspective view of the same tricycle showing parts of the back, side and top thereof.

I claim:

The ornamental design for a tricycle or the like, as shown.

ROBERT T. COTTAM.
